Primary Examiner — Darcey E Gottschalk(74) *Attorney, Agent, or Firm* — Weiss & Arons LLP(57) **CLAIM**

The ornamental design for a bottle cap with UV LED, as shown and described.

DESCRIPTION

FIG. 1 is a top perspective view of a bottle cap with UV LED, showing my new design;

FIG. 2 is a bottom perspective view thereof;

FIG. 3 is a front elevation view thereof, the rear, right-side, and left-side elevation views being a mirror image thereof;

FIG. 4 is a top plan view thereof; and,

FIG. 5 is a bottom plan view thereof.

The broken lines depict portions of the bottle cap with UV LED that form no part of the claim.
